US00D552425S

(12) **United States Design Patent** (10) Patent No.: **US D552,425 S**
Hayes et al. (45) Date of Patent: ** Oct. 9, 2007

(54) **CONTAINER**

(75) Inventors: **Thomas J. Hayes**, McHenry, IL (US);
Scott D. Brown, Winthrop Harbor, IL
(US); **H. Bernard Kirkland**,
Lindenhurst, IL (US)

(73) Assignee: **Pactiv Corporation**, Lake Forest, IL
(US)

(**) Term: **14 Years**

(21) Appl. No.: **29/223,331**

(22) Filed: **Feb. 11, 2005**

2,125,793 A	8/1938	Linderman, Jr.
RE20,934 E	12/1938	Collins
2,260,651 A	10/1941	Annen
2,720,332 A	10/1955	Holt
2,738,915 A	3/1956	St. Clair
2,798,631 A	7/1957	Engel
2,986,300 A	5/1961	Parrish
2,999,611 A	9/1961	Paulson
3,007,602 A	11/1961	Frank
3,049,259 A	8/1962	Mazzi et al.
3,097,780 A	7/1963	Witmer
